United States Patent Office

Des. 202,371
Patented Sept. 21, 1965

202,371

REFRACTOR FOR LIGHTING FIXTURES AND THE LIKE

Vearl S. Wince, Newark, Ohio, and Carl X. Meyer, St. Louis, Mo., assignors of one-half to Holophane Company, Inc., New York, N.Y., a corporation of Delaware, and one-half to Emerson Electric Manufacturing Company, St. Louis, Mo., a corporation of Missouri

Filed Feb. 19, 1964, Ser. No. 78,694

Term of patent 14 years

(Cl. D48—16)

FIG. 1 is a view in perspective of a refractor for lighting fixtures showing my new design;

FIG. 2 is a side view of the refractor of FIG. 1;

FIG. 3 is a top view of the refractor;

FIG. 4 is a bottom view of the refractor;

FIG. 5 is an end view of the refractor.

We claim:

The ornamental design for refractor for lighting fixtures and the like, substantially as shown and described.
